PERCUSSION DRUM

Charles P. Cordes, Elizabeth, N. J.

Application May 3, 1944, Serial No. 533,878

4 Claims. (Cl. 84—415)

1

This invention relates to percussion drums, and an important object of the present invention is to provide a novel drum head construction for drums of this kind, in which simple and efficient means is provided for tensioning the skin of the drum head by application of power at a single point.

A more specific object of the present invention is to provide a drum head construction of the above kind which is comparatively simple, compact, and otherwise well adapted to meet with the requirements for a successful commercial use.

Another important object of the present invention is to provide, in a snare drum, a snare carrier, and means to mount the snare carrier upon the head of the drum so that said snare carrier is yieldingly urged toward and into operative relation with the skin of the drum head, whereby, when "choking" is about to occur, the snare carrier will yield from the skin of the drum head and permit a smooth flow of opposing vibrations between the snares and the skin of the drum head.

Another object of the present invention is to provide in a snare drum characterized as set forth above, a snare carrier embodying simple and efficient means for tensioning the snares.

Still another object of the present invention is to provide, in a snare drum characterized as set forth above, simple and efficient manually operable means for moving the snare carrier toward or away from the skin of the drum head so as to render the snares operative or inoperative at will.

With the above general objects in view, and others that will become apparent as the nature of the invention is better understood, such invention consists in the novel form, combination and arrangement of parts hereinafter more fully described, shown in the accompanying drawings and claimed.

In the drawings, wherein like reference characters indicate corresponding parts throughout the several views:

Figure 1 is a plan view of a snare drum embodying the present invention.

Figure 2 is an elevational view thereof, partly broken away.

Figure 3 is a fragmentary elevation looking toward the right of Figure 1 and drawn on an enlarged scale.

Figure 4 is a fragmentary vertical section taken

2

substantially upon the plane of line 4—4 of Figure 3.

Figure 5 is an enlarged fragmentary section taken on line 5—5 of Figure 1.

Figure 6 is a transverse section taken on line 6—6 of Figure 4.

Figure 7 is a fragmentary section taken on line 7—7 of Figure 4.

Figure 8 is a view similar to Figure 7 taken on line 8—8 of Figure 4.

Figures 9 and 10 are fragmentary perspective views of details of the invention.

Figure 11 is an elevational view, partly broken away, of the preferred form of detachable handle for rotating the pinion which actuates the tensioning ring of the drum head construction.

I have illustrated in the accompanying drawings a snare drum including a shell 5 having similar head constructions at opposite ends thereof, so that a description of one head construction will suffice for both. As shown, each end of the shell 5 is inwardly offset, as at 6, or externally reduced in diameter to provide the reduced end portion 7 and an external annular shoulder 8 at the inner end of the reduced end portion 7. Snugly fitted on the reduced end portion 7 is an externally threaded ring 9 that is seated flatly on the shoulder 8 and secured to the shell 5 by means of screws 10 passing through the ring 9 and threaded into said shell 5. An internally threaded retaining hoop 11 is screwed at its inner portion upon the threaded ring 9 so as to be adjustable longitudinally of the shell 5, and this retaining hoop has an annular inwardly projecting flange 12 at its outer end. The inner portion 12' of flange 12 is preferably inclined inwardly, as shown clearly in Figure 5. A tensioning ring 13 is threaded in the outer portion of the retaining hoop 11 and has its outer portion provided with external gear teeth

14 so that it also constitutes a ring gear. The inner portion 13' of the outer face of tensioning ring 13 is also preferably inclined inwardly the same as the inner portion of flange 12 of the hoop 11. At a suitable point circumferentially

thereof, the retaining hoop 11 is provided with a transverse hollow rib 15 having a cylindrical bore 16 parallel with the axis of shell 5 and in which is journaled the shaft 17 having a pinion 18 rigid with the outer end thereof and disposed and 50 suitably retained within a counterbore 19 in the

outer end of the rib 15. Pinion 18 meshes with the teeth 14 of tensioning ring 13, as clearly shown in Figures 1 and 5.

An annular space *a* is provided between the retaining hoop 11 and the reduced end portion 7 of shell 5, and disposed in this space inwardly of the tensioning ring 13 is a flesh hoop 20 consisting of an annular channel of V-shaped cross section having inturned flanges 21a along the free edges thereof. The usual skin disc 21, or circular sheet of skin, is stretched over the end of shell 5 and has its marginal portion wrapped about the flesh hoop 20 with its free marginal portion tucked into the channel 20' of hoop 20 through the open outer side of the latter. Disposed between the tensioning ring 13 and the hoop 20 is a thin thrust ring 22 having a central inward annular corrugation 23 projecting toward the opening 20a in the outer side of the flesh hoop 20. Bearing balls 24 are mounted in sockets 24' provided at suitable intervals in the inner surface of tensioning ring 13, and these balls project and engage in the groove 23 of thrust ring 22. Balls 24 may be rotatably held in place by peening the material of the ring 13 inwardly as at 24a so as to envelope slightly more than one-half of said bearing balls. This construction permits free rotation of tensioning ring 13 relative to thrust ring 22, allowing the latter to remain still or to be held stationary by its frictional contact with the adjacent portion of the skin 21. Obviously, by rotating pinion 18, tensioning ring 13 may be turned and threaded inwardly, thereby causing thrust ring 22 to force the adjacent portion of skin 21 into the opening at the outer side of hoop 20, thereby securely securing the marginal portion of the skin to the flesh hoop and forcing the latter inwardly to tension the skin 21 over the outer end of the end portion 7 of the shell, as desired. Due to the relatively great thickness of the pinion 18 and the teeth of tensioning ring 13, they will remain in mesh even though the ring 13 is adjusted axially of the shell relative to pinion 18 to place the skin 21 under tension. As shown clearly in Figure 1, the shaft 17 and pinion 18 have an axial bore 25 of polygonal cross section so that a suitable tool with a squared end may be engaged in this bore for turning the pinion 18. A preferred form of tool for this purpose is shown in Figure 11, wherein a square shank 26 projects from the intermediate portion of a handle member 27 at right angles to the latter, and similar shorter shanks 28 project from opposite ends of said handle member 27. The shanks 26 and 28 are all of the same size and shape so as to fit the bore 25. Thus, any one of the shanks may be engaged in the bore 25 for turning pinion 18, thereby enabling actuation of the latter from different angles. As the thrust ring 22 may remain stationary and as it bears upon the skin 21, there is no tendency to cause the skin to rotate with the tensioning ring 13. In this way, the skin is drawn evenly at all points so as to be tensioned in a very smooth condition. By threading the retaining hoop 11 on the shell, it may be adjusted longitudinally of the latter so that the flange 12 is positioned in proximity to the skin 21 so that most efficient tensioning of the skin may be effected by relatively slight turning of the tensioning ring 13.

It will thus be seen that I have provided a durable and compact drum head construction in which simple and efficient means is provided for tensioning the skin of the drum head, and in

which such tensioning means is operable by the application of power at a single point.

Snares 29 are disposed diametrically of and at the outer side of the skin 21 of one of the drum heads, said snares being attached to a carrier 30 that embodies means for tensioning the snares 29 and that is yieldingly urged by means of springs 31 toward the skin 21 to normally position the snares 29 in operative relation to said skin 21. As shown, the carrier 30 includes a suitable frame composed of spaced parallel channels 32 rigidly connected at their ends by cross members 33 and 34. A transverse tensioning bar 35 is disposed adjacent and outwardly of the cross bar 33 and is provided with spaced guide pins 36 slidably fitting into guides 37 secured in the adjacent ends of the channel frame members 32. The snares 29 are attached in any well known manner at corresponding ends to a transverse attaching bar 38 secured to the cross bar 34, and the other ends of said snares are similarly attached to an attaching bar 39 secured to the tensioning bar 35. The bars 34 and 35 are preferably in the form of angles having upstanding outer flanges provided with apertures 35' which receive tongues 40 struck from the attaching bars 38 and 39 and clinched behind the vertical flanges 35a of the bars 34 and 35 so as to secure the adjacent bars together. If metallic snares are used, they may be soldered to bars 38 and 39 as at 40', while any preferred means of attachment may be provided for the snares if other than metallic snares are employed. Fixed to the under side of the tensioning bar 35 by welding or the like is a nut 41 through which is adjustably threaded an adjusting screw 42 that has a pointed inner end 43 bearing in a recess 43a or small opening of the cross bar 33. The screw 42 projects outwardly beyond the adjacent side of the retaining hoop 11 and has a knob 44 on its outer end to facilitate turning of the same. By adjusting screw 42 inwardly, the tensioning bar 35 may be forced away from the adjacent end of frame 30 so as to place the snares 29 under tension. Opposite turning of screw 42 will reduce the tensioning of snares 29 in an obvious manner.

Rigid with diametrically opposite portions of the retaining hoop 11 at the outer end of the latter are supporting elements including pairs of spaced parallel arms 45 that project inwardly in spaced parallel relation to the skin 21 outwardly of the latter. These arms 45 terminate adjacent but inwardly of the ends of the frame 30 and have their inner ends rigidly connected by cross bars 46. The springs 31 bear at corresponding ends upon the inner ends of the arms 45 and at their other ends against the ends of angular brackets 47 welded or otherwise rigidly attached at 47' to the outer sides of the channel frame members 32. The ends of springs 31 may be suitably attached to arms 45 and brackets 47, such as by soldering, welding or the like. Attached at their ends to the frame members 32 adjacent but inwardly of the inner ends of the pairs of arms 45 are substantially V-shaped yokes 48 having flat intermediate portions 49 and a right angular portion 50 at one side of each intermediate portion 49. Journalized in bars 46 of the supporting elements intermediate the arms 45 parallel with the latter and extending from one cross bar 46 to the other is a shaft 51. The shaft 51 has a pair of laterally projecting cam lugs 52, each of which is coincident with the flat intermediate portion 49 of a different one of the yokes 48, the shaft 51 being disposed in con-

tact with the flat portions 49 and the right angular portions 50 of said yokes 48. The arrangement is such that when the shaft 51 is turned so as to dispose the lugs 52 parallel with the skin 21, the springs 31 are permitted to urge the snare carrier toward the skin 21 of the drum head so as to operatively position the snares 29 in relation to said skin. On the other hand, when the shaft 51 is rotated in a counter-clockwise direction, as viewed in Figure 3, the cam lugs 52 will be caused to engage the flat portions 49 and press the yokes 48 outwardly, thereby withdrawing the snare carrier from the skin 21 and rendering the snares 29 inoperative. When the latter takes place, the flat outer ends 52' of the lugs 52 will engage the flat portions 49 of the yokes 48 at a point slightly past the axial center of the shaft 51 so that the snare carrier will be retained in inoperative position. On the other hand, when the shaft 51 is turned in the opposite direction for a very slight distance so that the lugs 52 pass to the opposite side of the axial center of shaft 51, the springs 31 will act to instantaneously rotate the shaft 51 for the remaining distance in this direction and the springs 31 will act to instantaneously force the snare carrier toward the skin of the drum head so as to render the snares operative. Obviously, when the snare carrier 30 is allowed to move inwardly to operative position, the lugs 52 are disposed parallel with the skin 21, as shown in the drawings. On the other hand, the lugs 52 point away from the skin 21 when they are moved to the position wherein they shift the snare carrier away from the skin 21 of the drum head.

As shown more clearly in Figure 4, one end 51' of the shaft 51 projects outwardly beyond the adjacent side of the retaining hoop 11 where it is equipped with a crank arm 53 connected at its outer end to the outer end of a push rod 55 by a pin and slot connection 54, said push rod being slidably mounted in a guide 56 carried by the retaining hoop 11. The rod 55 is mounted to slide longitudinally of the drum shell 5 and is formed at its inner end with a thumb piece 57. By pressing outwardly on the thumb piece 57, the shaft 51 is caused to rotate in a direction to move the snare carrier to inoperative position. Return of the snare carrier to operative position may be effected by simply pulling inwardly on the thumb piece 57, as will be apparent. It will be particularly noted that the snares are moved away from the skin of the drum head without relieving the tension of said snares. Thus, the snares may be tensioned as desired and this tension will be maintained at all times until manually changed, regardless of whether the snares are operative or inoperative with respect to the skin of the drum head.

From the foregoing description, it is believed that the construction and operation, as well as the advantages of the present invention, will be readily apparent to those skilled in the art. Obviously, the invention is susceptible of various changes in details of construction illustrated and described without departing from the spirit and scope of the invention as claimed.

What I claim is:

1. In a snare drum, the combination with a shell having a skin stretched over an end thereof and provided with a retaining hoop, of diametrically opposed angular supporting elements rigid with and projecting outwardly from the retaining hoop and then toward each other, a rock shaft extending between and journaled in said support-

ing elements and disposed outwardly of and in spaced parallel relation to the skin, said rock shaft being provided with cam lugs, a floating snare carrier disposed parallel with and between the skin and said rock shaft, springs interposed between said supporting elements and the snare carrier and urging the latter toward and into operative relation to the skin, yokes fixed to the snare carrier and passing across the shaft outwardly of the latter, said yokes being engageable by the cam lugs to move the snare carrier away from the skin to an inoperative position and to retain the snare carrier in said inoperative position upon turning said rock shaft in one direction, said cam lugs further being releasable from the yokes to permit movement of the snare carrier toward and into operative relation to the skin by said springs upon turning said rock shaft in the opposite direction, and manually operable means carried by the retaining hoop and connected to one end of said rock shaft for turning the latter.

2. In a snare drum, the combination with a shell having a skin stretched over an end thereof and provided with a retaining hoop, of a snare carrier disposed at the outer side of and parallel with the skin, diametrically opposed supporting elements rigid with the retaining hoop and projecting toward each other outwardly of the snare carrier, springs interposed between said supporting elements and the snare carrier and uniformly urging the latter inwardly toward and into operative relation to the skin, a manually operable rock shaft disposed diametrically of the skin, said rock shaft extending between and being journaled in said supporting elements, and means operatively connecting said rock shaft to the snare carrier, said means being also releasable from the snare carrier to permit movement of said snare carrier relative to said rock shaft in response to vibrations of the skin and being operable upon turning said rock shaft to move the snare carrier outwardly from the skin to an inoperative position and to retain the snare carrier in said inoperative position.

3. In a snare drum, the combination with a shell having a skin stretched over an end thereof and provided with a retaining hoop, of a snare carrier disposed at the outer side of and parallel with the skin, diametrically opposed supporting elements rigid with the retaining hoop and projecting toward each other outwardly of the snare carrier, springs interposed between said supporting elements and the snare carrier and uniformly urging the latter inwardly toward and into operative relation to the skin, and manually operable means carried by said supporting elements to move said snare carrier outwardly from the skin to an inoperative position and to retain the snare carrier in said inoperative position, said means being also releasable from the snare carrier to permit movement of said snare carrier in response to vibrations of the skin.

4. In a snare drum, the combination with a shell having a skin stretched over an end thereof and provided with a retaining hoop, of a snare carrier disposed at the outer side of and parallel with the skin, supporting means rigidly connected with the hoop and disposed outwardly of the snare carrier, springs interposed between said supporting means and the snare carrier and uniformly urging the latter inwardly toward and into operative relation to the skin, and manually operable means carried by said supporting means to move said snare carrier outwardly from the skin

to an inoperative position, said means being also releasable from the snare carrier to permit movement of said snare carrier in response to vibrations of the skin.
